United States Patent Office

Des. 178,505
Patented Aug. 14, 1956

178,505

CHAIR

Frederick L. Duer, Bellwood, Ill.

Application February 17, 1955, Serial No. 34,548

Term of patent 14 years

(Cl. D15—1)

Figure 1 is a front perspective view of a chair, showing my new design, and

Figure 2 is a rear perspective view of a chair, showing my new design.

The dominant features of my design for a chair reside in those portions of the drawings shown in full lines.

I claim:

The ornamental design for a chair, substantially as shown and described.
